RAILWAY CAR CONSTRUCTION

Thomas F. Dwyer, Jr., Cambridge, Mass., and John Carl Hassett, West Haven, Conn., assignors to Fabreeka Products Company, Inc., Boston, Mass., a corporation of Massachusetts

Application February 17, 1936, Serial No. 64,310

10 Claims. (Cl. 213—222)

Our invention relates particularly to means for silencing railway car platforms. A prolific source of noise on railway passenger equipment is the movement of the buffer and guide stems through the platform. These stems carry the face and tread plates and support the vestibule diaphragm. The movement of these stems communicates noise to the platform and car frame and also wears the slots in the platform.

10 A main object of this invention is to provide a means for substantially eliminating the troublesome noise due to movement of the buffer bar and other bars.

Another object is to provide an effective silencing device which is simple in construction, easy to install and durable.

We have discovered that noise transmission can be practically eliminated and wear substantially reduced by providing special fabricated sleeves 20 which serve as guides for the buffer and guide stems in their movement back and forth in the platform. Each sleeve in the form shown consists of two channel-like sections placed edge to edge and each section consists of inner and outer 25 layers of metal with an intervening layer of a material which prevents the transmission of sound creating vibrations. For the most satisfactory results there should be no metallic connection between the sides of the bars and the 30 slots or passages in the platform.

Preferred forms of the invention are illustrated in the accompanying sheets of drawings, in which

Fig. 1 is a section and vertical end view of a fragment of a car showing the platform and 35 buffer stems.

Fig. 2 is a fragmentary section of the platform and two of the sleeves on a somewhat larger scale.

Fig. 3 is a longitudinal vertical sectional view 40 through the platform and showing one of the side buffer stems.

Fig. 4 is a fragmentary perspective showing one of the sleeves with the outer metal channel of the same length as the inner.

Fig. 5 is a sectional view similar to Fig. 3, the 45 section however being taken on the vertical plane through the center buffer stem guide sleeve.

Fig. 6 is a transverse sectional view of one of the sleeve sections.

50 Fig. 7 is a detail fragmentary longitudinal section of one end of a sleeve.

Fig. 8 is a longitudinal sectional view on a vertical plane showing a modified construction.

Fig. 9 is an enlarged fragmentary section of one 55 end of the guide sleeve shown in Fig. 8.

Fig. 10 is a longitudinal section through a guide for a circular buffer stem.

Fig. 11 is a section on the line 11—11 of Fig. 10.

Fig. 12 is a longitudinal section through another means for holding the buffer stem guide in position.

The platform construction illustrated is of the conventional type in which the platform frame 10 has passages for the usual center buffer stem 11 and the side stems 12, 12.

The guide sleeves for the stems of Figs. 1 to 9 are all substantially alike but of appropriate size to correspond with the stems and the passages provided for them in the platform. Each guide sleeve consists of two parts 14 and 15 which may conveniently be identical. Each section has an outer layer 16 which may preferably be of some material such as open hearth steel. The inner layer 17 is preferably of a wear resistant metal such as rolled manganese steel.

In the preferred form of the invention the sound-deadening or non-vibrant material 18 is tightly embraced by the inner and outer shells of steel and consists of a series of layers of fabric such as cotton duck 19 impregnated with a rubber compound and also preferably interspersed with thin layers of rubber all vulcanized into a laminated structure which is substantially unaffected by changes in temperature, water, oil and gas. The non-metallic material differs from a 30 rubber pad in at least two noteworthy respects, the first of which is that it has but little resiliency, and the second is that it has a remarkable capacity for absorbing sound or preventing the 35 transmission of sound producing vibrations.

A different type of cement is used to adhere the material 18 to the metal plates than that which is used to impregnate the material.

It will be noted that the edges of the non-metallic fabric 18 extend beyond the edges of the 40 metallic shell sections 16 and 17 so that when two of these channel sections are placed edge to edge as shown in Fig. 4, these non-metallic edges meet at 20 so as to provide a compressible fit between the halves of the sleeves to take up further sounds 45 and vibrations.

The sleeve sections are suitably secured in the 50 passages in the platform, for instance, by welding the ends of the outer layers at the point 21. Each sleeve is tightly fitted in its passage 22 in the platform and provides a guide passage for the associated buffer stem. In the form shown in Figs. 2 and 3 a chafing block 23 is shown, and a shim 24, for instance of open hearth steel, is also provided. These shims may be welded as at 25 55

to the casting and the sleeve section welded at 26 to the shim so as to prevent relative movement of these parts.

In the form shown in Fig. 5 there are shims or 5 filler plates 30 and 31 which may be welded in place as at 32. These constructions shown in Figs. 3 and 5 embody a size and design of non-vibrant sleeve adapted to be employed in an old form or preformed platform construction. The 10 form shown in Fig. 8 is designed to be used in a platform construction which itself is designed and built to accommodate the non-vibrant sleeve.

In this latter type of construction the sleeve 15 is intended to be removable and is held in place by a front plate 35. In this case we provide a layer of the special non-vibrant material 36 which is vulcanized or otherwise secured to the protruding edge 18 of the non-vibrant unit. It 20 will be seen that in this construction the rear end of the platform has a flange 37 which serves as an abutment for the sleeve so that the sleeve is held between the flange 37 and the front plate 35.

In making up the units the metal shells and 25 the non-metallic members are cemented together under considerable pressure so that when completed each composite sleeve may be handled, installed and used as a unit with no likelihood of the parts becoming separated when in use. 30 It will be seen that this invention makes it possible to dampen and substantially stop the transmission of troublesome noise vibrations and that the parts are of such a character that the sleeves may be readily inserted into any existing 35 type of construction without requiring modification.

This material has been found to be extremely durable as it is practically impossible to permanently deform it under pressure. It is not subject 40 to air vulcanization in the way that ordinary soft rubber is nor is it to any appreciable extent affected by long continued immersion in water or oil.

Furthermore it is not sufficiently resilient to 45 allow the setting up of sympathetic vibrations. It has none of the disadvantages of the highly compressible materials such as rubber and cork or other materials frequently proposed for silencing car structures.

The shock absorbing pad used in this invention 50 is applied between the inner and outer channel shaped plates under pressure of about fifty pounds per square inch to shape the bent portion of the pad and at a temperature of about 230° F. 55 for vulcanizing the cement with which the pad is impregnated. The laminated layers of fabric retard and slow up recoil from shocks so that while this shock absorbing material is flexible it is not 60 resilient and does not transmit sympathetic vibrations as freely as does rubber or other lively resilient materials.

An important feature of the present invention resides in the absence of any metal parts connecting the stem and the platform. Where such 65 metal connections exist, they assist rather than retard the transmission of sounds. The shock absorbing pad is cemented to the metal plates by another cement from that used in the pad to get the best results, thereby avoiding the use of bolts 70 or rivets which would tend to transmit lateral vibrations and build up noise.

A noteworthy feature of the present invention resides in having the two channel shaped halves 75 contiguous only along the edges of the shock absorbing pad which project toward the other

channel part and beyond the metal, thus precluding any metal to metal contact between channel plates.

The sound deadening guides of this invention are adapted for both the main and side buffer 5 stems.

In Figs. 10 and 11 a metallic tube or platform casting 40 encloses the buffer stem 45 and is provided with the sound deadening guide units between the stem and such member 40. The sound 10 deadening unit includes the shock absorbing material 41 shown as being of cylindrical shape outside of the wear resisting manganese steel bushing 42. The bushing 42 and the material 41 are preferably cemented together under pressure and then the material 41 is inserted into the cylindrical member 40 and cemented thereto. To 15 prevent the buffer stem guide from being moved longitudinally outward a washer 43 is welded at 44 to the member 40. If desired the material 20 41 and the sleeve 42 may extend entirely through the member 40, although in the form shown by Fig. 10 this shock absorbing guide is not made continuous but in two parts as illustrated.

In Fig. 12 the steel platform casting 50 is of 25 the general shape shown in Figs. 3 or 5 for example except that at its inner end portion there is provided a flange or shoulder 51 adapted to engage the buffer stem guide to prevent the guide bearing unit being moved inwardly beyond 30 said flange 51. As before the guide bearing unit includes inner and outer plates 52 and 54 which are of channel shape as indicated in Figs. 2 and 4 for example, with a layer 53 of the same 35 shock absorbing material previously described.

To prevent the buffer stem guide unit from being moved outwardly in use the outer channel plates 54 are welded at 55 to the frame 50. The outer channel plates at their forward end, as shown in Fig. 12, extend longitudinally beyond the shock absorbing material and inner plates whereas at the inner end of the guide bearing both plates and the shock absorbing material are substantially flush as illustrated.

Although the multi-ply fabric herein described 45 is by far the best material for the purpose, some of the advantages of the split tube guide free of metallic connections through the fabric may be attained with other material provided the device is free of metallic means for transmitting metal 50 to metal contact vibrations from the sides of the stems to the platform and vice versa.

We claim:

1. In a railway car, a buffer stem guide comprising a channel shaped member including inner and outer channel shaped metal plates with non-metallic shock absorbing material held therebetween and free from metal to metal contact through the non-metal shock absorbing material, a supporting frame around said member, 60 said member being held in position by having the outer channel plate extended and secured longitudinally beyond the inner plate and shock absorbing material and being secured to said frame beyond said inner plate and shock absorbing 65 material.

2. A bar or stem guide comprising a channel member between the sides of which the stem is located, said member including inner and outer channel plates having a shock absorbing material therebetween and extending transversely beyond the ends of said plates on each side of the channel and in a direction away from the base of the channel, and a member closing said channel member and adapted to lie substantially contiguous 75

uous the stem, said last mentioned member also having inner and outer plates between which shock absorbing material is placed, the plates of said last mentioned member being held out of metallic contact with the plates of the channel member by the transversely projecting portions of said shock absorbing material.

3. A platform frame having a passage and a bar or stem guide therein comprising a channel member between the sides of which the stem is located, said member including inner and outer channel plates having a shock absorbing material therebetween and extending transversely beyond the ends of said plates on each side of the channel and in a direction away from the base of the channel, and a member closing said channel member and adapted to lie substantially contiguous the stem, said last mentioned member also having inner and outer plates between which shock absorbing material is placed, the plates of said last mentioned member being held out of metallic contact with the plates of the channel member by the transversely projecting portions of said shock absorbing material, said outer plates being welded to the platform frame longitudinally beyond an end of said shock absorbing material and inner plate and the shock absorbing material being cemented to each of its contiguous plates.

30 4. A guide for a reciprocating stem comprising two channel-like members arranged to form between them a tubular guide passage, each member being composed of an inner and outer metallic channel with interposed layers of shock absorbing material, at least one of said shock absorbing layers extending beyond the edges of the adjacent metallic members and preventing said metallic members from contacting with each other.

40 5. As an article of manufacture, a guide member consisting of inner and outer metallic channel members with an interposed layer of shock absorbing material extending beyond the edges of the channel members, the outer channel member having a portion extending beyond its end for attaching said member to the wall of a platform guide passage.

6. A guide for a reciprocating stem comprising pairs of inner and outer plates, at least one pair being channel shaped to receive said stem, sound deadening material between the plates of each pair, said material comprising layers of fabric impregnated with rubber and having thin layers of rubber therebetween, said sound deadening material being constructed and arranged to form common means for holding the pairs of plates

spaced apart and non-metallic means for fastening said inner and outer plates.

7. In a car construction, a device for deadening the sound waves between a reciprocating metallic stem and its surrounding metallic support consisting of a channel member formed of sound deadening material shaped to conform to said stem and rigid members only partially encircling said shaped material for maintaining the channel shape of said sound deadening material, said material including layers of fabric impregnated with rubber and having layers of rubber therebetween and non-metallic means for holding the members in position thereby preventing metal to metal contact from the stem to the support.

8. Means for preventing transmission of vibrations from a rod to its support which comprises a tubular member formed of two complementary parts, each of which has a layer of non-metallic, flexible but substantially non-compressible material with metallic inner and outer holding plates and plates of each part together and preventing metal to metal connection between the inner and outer plates, said non-metallic material extending beyond said plates for preventing the plates of one part from touching the plates of the other part.

9. In a railway car, a buffer stem guide unit comprising non-metallic shock absorbing material contiguous a metal member and channel-shaped to conform to said stem, another metal member contiguous additional non-metallic shock absorbing material on the opposite side of said stem from said first mentioned shock absorbing material, at least one of said metal members being of less extent in cross section than its contiguous shock absorbing material whereby said material prevents any metal to metal contact between said members, and means for holding said unit against longitudinal movement with said stem.

10. In a railway car, a buffer stem guide unit comprising an outer metal member, an inner metal member, said inner and outer metal members being spaced apart throughout their entire extent, non-metallic shock absorbing material between said inner and outer metal members, and metallic means engaging an end portion of said outer metal member and spaced from contact with said inner metal member for holding said unit in place against longitudinal movement whereby any metal to metal contact between said outer metal member and the inner metal member is avoided.

THOMAS F. DWYER, JR.
